Primary Examiner—B. J. Bullock

(74) Attorney, Agent, or Firm—David A. Burge

(57) **CLAIM**

We claim the ornamental design for a housing for latches and locks, as shown and described.

DESCRIPTION

FIG. 1 is a perspective view showing front portions of our new design;

FIG. 2 is a perspective view showing rear portions thereof;

FIG. 3 is a front side elevational view thereof;

FIG. 4 is a rear side elevational view thereof;

FIG. 5 is a bottom view thereof, it being understood that a top view would be a mirror image reversal of this view;

FIG. 6 is a left end view thereof; and,

FIG. 7 is a right end view thereof.
